(57) CLAIM

We claim the ornamental design for an appliance recessed window bezel, as shown and described.

DESCRIPTION

FIG. 1 is a front perspective view of an appliance recessed window bezel of the present disclosure; and, FIG. 2 is a front elevational view of the appliance recessed window bezel of FIG. 1. The broken lines are for illustrative purposes only and form no part of the claimed design.

1 Claim, 2 Drawing Sheets

FIG. 1

FIG. 2
